(57) **CLAIM**

The ornamental design for an X-ray digital imaging apparatus, as shown and described.

DESCRIPTION

FIG. 1 is a front view of a first embodiment of an X-ray digital imaging apparatus showing our new design;

FIG. 2 is a rear view of the first embodiment of the X-ray digital imaging apparatus;

FIG. 3 is a left side view of the first embodiment of the X-ray digital imaging apparatus;

FIG. 4 is a right side view of the first embodiment of the X-ray digital imaging apparatus;

FIG. 5 is a top plan view of the first embodiment of the X-ray digital imaging apparatus;

FIG. 6 is a front perspective view of the first embodiment of the X-ray digital imaging apparatus showing our new design;

FIG. 7 is a rear perspective view of the first embodiment of the X-ray digital imaging apparatus;

FIG. 8 is a front perspective view of the first embodiment in an operational position of the X-ray digital imaging apparatus;

FIG. 9 is a front view of a second embodiment of the X-ray digital imaging apparatus;

FIG. 10 is a rear view of the second embodiment of the X-ray digital imaging apparatus;

FIG. 11 is a left side view of the second embodiment of the X-ray digital imaging apparatus;

FIG. 12 is a right side view of the second embodiment of the X-ray digital imaging apparatus;

FIG. 13 is a top plan view of the second embodiment of the X-ray digital imaging apparatus;

FIG. 14 is a front perspective view of the second embodiment of the X-ray digital imaging apparatus showing our new design;

FIG. 15 is a rear perspective view of the second embodiment of the X-ray digital imaging apparatus; and,

FIG. 16 is a rear perspective view of the second embodiment in an operational position of the X-ray digital imaging apparatus.

The bottom plan views of the first and second embodiments are omitted.
